UNITED STATES PATENT OFFICE

131,055

DESIGN FOR A COMBINED RADIO AND PHONOGRAPH CABINET

Howard S. Bennett, Scotia, N. Y.

Application September 25, 1941, Serial No. 103,688

Term of patent 7 years

To all whom it may concern:

Be it known that I, Howard S. Bennett, a citizen of the United States, residing at Scotia, county of Schenectady, and State of New York, have invented a new, original and ornamental Design for a Combined Radio and Phonograph Cabinet, of which the following is a specification, reference being had to the accompanying drawing, forming a part thereof in which—

Fig. 1 is a front perspective view of the combined radio and phonograph cabinet showing my new design,

Fig. 2 is a front perspective view of the cabinet in which the left hand door is open, with the right hand door dropped down and exposing the control panel, and

Fig. 3 is a side elevational view thereof.

The rear of the cabinet is substantially plain.

I claim:

The ornamental design for a combined radio and phonograph cabinet, as shown and described.

HOWARD S. BENNETT.
